UNITED STATES PATENT OFFICE.

WILLIAM A. SCHRAUBSTADTER, OF ST. LOUIS, MISSOURI, ASSIGNOR TO
INLAND TYPE FOUNDRY, OF ST. LOUIS, MISSOURI, A CORPORATION OF MISSOURI.

DESIGN FOR A FONT OF TYPE.

SPECIFICATION forming part of Design No. 37,414, dated April 18, 1905.

Application filed October 8, 1904. Serial No. 227,736. Term of patent 14 years.

To all whom it may concern:

Be it known that I, WILLIAM A. SCHRAUBSTADTER, a citizen of the United States, and a resident of the city of St. Louis and State of Missouri, have invented a new, original, and ornamental Design for a Font of Type, of which the following is a specification.

My design consists in the features shown in the accompanying drawing, which forms part of this specification.

What I claim as new, and desire to secure by Letters Patent, is—

The ornamental design for a font of type herein shown.

St. Louis, Missouri, August 16, 1904.

WM. A. SCHRAUBSTADTER.

In presence of—

FRED F. REISNER,
